CLAIM

The ornamental design for a finger-gripped smoking device, substantially as shown and described.

DESCRIPTION

FIG. 1 is a perspective view of the finger-gripped smoking device showing my new design;;

FIG. 2 is a front elevational view of the finger-gripped smoking device showing my new design;;

FIG. 3 is a rear elevational view of the finger-gripped smoking device showing my new design;;

FIG. 4 is a left side view of the finger-gripped smoking device showing my new design;;

FIG. 5 is a right side view of the finger-gripped smoking device showing my new design;;

FIG. 6 is a top plan view of the finger-gripped smoking device showing my new design; and,

FIG. 7 is a bottom plan view of the finger-gripped smoking device showing my new design.

The broken lines which are immediately adjacent the shade lines and which connect the contour line of the finger-gripped smoking device represent the bounds of the claim. The remaining broken lines between the left and right sections illustrate portions of the article. None of the broken lines forms part of the claimed design.
